METHOD AND APPARATUS FOR STRINGING
TOBACCO

John Robert Bass, Danville, Va.

Application November 21, 1931, Serial No. 576,594

9 Claims. (Cl. 131—21)

This invention relates to the handling and curing of tobacco, and more particularly to apparatus for stringing tobacco leaves, preparatory to housing.

5 In some tobacco growing sections, it is the practice to cut down the entire plant and hang the plants in the barn for curing, the plants being usually impaled upon a housing stick and the filled sticks being supported in the barn on tier poles.

10 In other sections, it is the practice to strip the leaves from the stalks of the plants and hang the leaves only in the barn for curing. This is especially true in the handling of certain

15 grades of tobacco, such, for example, as the finer grades known as "cigar leaf". Such a method permits gathering only the ripe or mature leaves from the plant, leaving the stalk standing and thus permitting the greener leaves

20 to mature.

The present invention relates particularly to the second of the above described methods of handling tobacco, namely, that method in which only the leaves, as distinguished from the entire plant, are housed in the barn. In following this method, it has heretofore been the practice to assemble the leaves on a cord or thread, thus forming a string, this operation being known as stringing. It has also been proposed to form 25 a string by sewing the leaves to a cloth band or tape. In either case, the idea has usually been to hang the strings of leaves in the barn by stretching them between tier poles.

It has been found, in practice, however, that 30 this method of housing the strings by stretching them between tier poles is troublesome and commercially unsatisfactory.

One of the objects of the present invention is, therefore, to devise a practical method for supporting strings of tobacco leaves on the usual housing sticks which rest upon the tier poles, and thus avoid the necessity of securing the strings to the tier poles.

Another object is to provide an improved 45 means for stringing tobacco leaves by using a sewing machine, but without the use of any band or tape.

A still further object is to provide improved means for forming a continuous string of tobacco leaves and for cutting such string into units or sections of the desired length for housing.

Other subsidiary objects and advantages will appear as the description proceeds.

In order that the invention and one means 50 for carrying it into effect may be readily under-

stood, reference is had to the accompanying drawings, forming part of this specification, and in which:

Figs. 1 and 1^a, taken together, illustrate a side elevation of the complete apparatus; 5

Figs. 2 and 2^a together illustrate a plan view of such apparatus;

Figs. 3 and 4 are front and side elevations respectively, on an enlarged scale, of a combined gripping and cutting device hereinafter 10 more fully described;

Fig. 5 is a view similar to Fig. 4, but showing the gripping and cutting device in a different position;

Fig. 5^a is a horizontal section on a still further 15 enlarged scale, substantially on the line 5^a—5^a of Fig. 5, showing the construction of the jaws of the gripping and cutting devices;

Fig. 5^b is a section substantially on the line 20 5^b—5^b of Fig. 1, looking in the direction of the arrows;

Fig. 6 is a section on an enlarged scale, substantially on the line 6—6 of Fig. 1^a, looking in the direction of the arrows;

Fig. 7 is a fragmentary sectional plan taken 25 substantially on the line 7—7 of Fig. 1, looking in the direction of the arrows;

Fig. 8 is a fragmentary sectional view, taken substantially on the line 8—8 of Fig. 1; and

Fig. 9 is a fragmentary perspective view illustrating my improved string of tobacco leaves as it appears when mounted astride a housing stick. 30

Referring to the drawings in detail, it may be explained in advance that the complete apparatus, the assembly of which is illustrated in Figs. 1, 1^a and 2, 2^a is designed to sew together tobacco leaves to form a continuous string, to cut this string into sections of desired length, and to place each section longitudinally astride a housing stick, so that the stick, carrying the section of string, may be placed in position on the tier poles. 35

Referring to the drawings, I employ, in connection with my improved apparatus, a sorting table 1, on which the leaves to be strung are delivered. The apparatus itself comprises a suitable frame 2 carried on legs 3. 40

Supported on the frame is a top or working surface 5, which may conveniently be formed of sheet metal and which is disposed substantially in the same plane as the sorting table 1. 45

Mounted in the frame immediately adjacent the edge of the sorting table is a roller 6, secured to a shaft 9, and at the other end of the top 5 is a similar roller 7, supported on but free to turn with respect to a shaft 10. 50

Running over the rollers 6 and 7 and supported upon the top 5 is a travelling belt or apron 8, preferably formed of canvas or the like, and constituting a conveyor for feeding the leaves forward from the sorting table.

As above stated, the roller 7 is free to turn on its shaft 10, but is normally locked thereto by means of a clutch member 11 keyed to the shaft, the member 11 and the end of the roller 7 being provided with cooperating clutch surfaces 11^a, as clearly shown in Fig. 6. The clutch member 11 is formed with an annular groove in which freely works the bifurcated end 12 of a control or shifting rod 13. This passes freely through a member 16 of the frame and carries at its end a roller 14, a helical spring 15 surrounding the rod and being interposed between the roller and the frame member 16. This spring tends to move the rod and roller toward the left and to draw the clutch member 11 out of engagement with the roller 10. The clutch member is normally held in driving relation to the roller 7 by a gear wheel 17 against the face of which the roller 14 bears. This gear wheel is provided at one side with a relatively short arcuate cam slot 18 (see Fig. 1^a) disposed in line with the rod 13, so that during a small part of each revolution of the wheel 17, the roller 14 drops into such slot, under the influence of the spring 15, thus shifting the clutch member 11 to the left, out of engagement with the roller 7, thereby temporarily interrupting the rotation of the roller 7 and hence the travel of the conveyor belt 8.

The machine may be driven either by hand or by foot power or by any suitable motor. By way of illustration, I have shown it as operated by foot power. To this end, I provide a crank shaft 19 journalled in the frame of the machine at one end and at the other end in a suitable bracket 20. The shaft 19 is provided with a pair of cranks 21 which are secured by connecting rods to the ends of a pair of treadles 22, hinged to a frame member 4. It is obvious that an operator, by working the treadles 22, can rotate the shaft 19 and thus drive the machine.

The shaft 19 carries a bevel gear 23 meshing with a bevel gear 24, secured to a shaft 29, which bevel gear 24 also meshes with and drives a third bevel gear 25 secured to the upper end of a vertical shaft 26, journalled in the frame and carrying a substantial fly wheel 27. Also secured to the shaft 26 adjacent the fly wheel is a spur gear 28, hereinafter further referred to.

The shaft 29 carries at its end a spur gear 30 meshing with an idler pinion 31, which in turn meshes with and drives a gear 32 secured to the end of the shaft 10. Thus, the shaft 10 is driven from the driving shaft 19 and imparts rotation to the roller 7 by means of the clutch 11, above described.

The gear wheel 17, which controls the position of the clutch, is rotated by means of a pinion 33, also secured to the shaft 10.

Also fixed to the shaft 29 is a pulley 34, over which passes a belt 35 which extends upwardly and drives a pulley 36 on a sewing machine 37. This sewing machine is conventionally illustrated in the drawings and may be of any suitable type. It is desirable, however, that it be of the chain stitch type, so that the stitches may be readily unravelled. It will be further understood that I prefer using either a single thread chain stitch machine or a machine employing two threads and producing what is known as a double chain stitch. This latter type of machine is that which is com-

monly employed for sewing up the ends of sacks of sugar, feed, etc., and is particularly suitable for my purposes, although any type of machine can be used which makes stitches in such manner that they can readily be unraveled by pulling one of the threads.

As is well known, chain stitch machines, and especially double chain stitch machines, are capable of looping the thread or threads together to form a series or chain of stitches, regardless of whether or not any fabric or other material is interposed. Thus, in sewing up the ends of sacks, as above mentioned, it is the common practice to extend or continue the chain of stitches beyond the fabric so as to form a projecting end or cue, this serving to prevent accidental unravelling. Therefore, by employing a machine of this type, I am enabled to unite the stems of tobacco leaves to form a string simply by feeding the stems successively under the needle and connecting them solely by the loops of thread forming the chain stitches, some of such stitches passing through the stems themselves and others lying in the spaces between the stems.

As above stated, the machine conventionally illustrated in Fig. 6 may be of any suitable type, but I have shown a spool of thread 37^a mounted thereon in the usual way, the thread from this spool passing down through suitable tension and feed devices to the needle 38.

To assist in properly spacing and feeding the leaves under the needle of the sewing machine, I preferably employ, in addition to the travelling conveyor 8, a force feed device shown as consisting of an endless chain or belt 39, having pins 35 projecting therefrom. This chain passes around a pair of pulleys 40 and 41, the latter being secured to a driving shaft 42, and the former being journalled at the forward end of a bracket 43, pivotally mounted upon the shaft 42, so that the pulley 40 and the forward end of the belt is capable of free vertical movement to accommodate varying thicknesses of material. The other end of the shaft 42 carries a pulley 44, which is driven by means of a belt 45 from a pulley 46 secured to the shaft 9 (see Fig. 2^a). The shaft 42 is journalled in a bracket 43^a adjustably secured to the frame of the machine by bolts 43^b passing through slots in the same (not shown).

In order to guide the leaves in their passage toward the sewing machine, I provide an adjustable gauge or butting board 47. This is secured to the top of the machine by means of brackets 48 having slots through which work clamping screws 49. Thus, the distance of this gauge or board from the conveyor belt 8 and from the needle of the sewing machine can be adjusted as desired.

Meshing with the gear 28 is a pinion 50, journalled in suitable bearings, and having pivoted thereto one end of the connecting rod 51, (see Fig. 2^a), the other end of which is secured to one arm of a bell crank lever 52 pivoted at 53 to the frame. Thus, as the gears 28 and 50 revolve, the bell crank lever 52 is oscillated.

In order to hold the stems of the leaves in position, as they pass under the needle of the sewing machine, I provide a presser bar 54. This is secured at one end to the lower end of a supporting rod 56, passing upwardly through a bracket 57 carried by the head of the sewing machine, and having its upper end threaded and provided with a nut 58, by means of which the rod and the presser bar may be vertically adjusted, as desired. A spring 55 surrounds the 75-

rod 56 and is interposed between the presser bar 54 and the bracket 57, as clearly shown in Fig. 6, to rigidly press the same downward as the stems of the tobacco leaves pass under it.

5 The bar 54 is elongated and extends a relatively great distance beyond the sewing machine and conveyor belt 8. It is also given a quarter twist, which progresses uniformly throughout its length, so that, while the end adjacent the sewing machine is substantially horizontal, the remote end, as shown in Figs. 1 and 2, is secured to one or more supporting rods 59, slidably mounted in a block 61, springs 60 surrounding the rods and being interposed between such block and the bar 54, whereby the bar is resiliently urged away from the block. This block 61 is carried by a bracket 62 adjustably secured by a slotted connection and bolt 63 to another bracket 64, attached to a part of the frame 2.

Substantially coextensive with the presser bar 50 and having a similar quarter twist in its length is a third conveyor belt 65, preferably similar to the belt 39 and having pins projecting from its surface to engage the stems of the tobacco leaves. This belt 65 passes around a pulley 66 mounted on the shaft 10 adjacent the sewing machine needle, as clearly shown in Fig. 6, and also around a horizontal pulley 67, secured to a shaft 68, journaled in the bracket 62. A guiding or supporting bar 65 is supported on the frame of the machine in such a position as to be substantially coextensive with that run of the belt 65 which is adjacent the presser bar 64, so that the belt runs in substantial contact with this bar. The edge of the bar adjacent the belt 65 is likewise formed with a quarter twist, so that it conforms with the configuration of the belt and serves to rigidly support the belt as the latter travels along. By reference to Fig. 2, it will thus be seen that the space between the bar 54 and the adjacent run of the belt 65 constitutes a throat or passage along which the string of tobacco leaves travels as it leaves the sewing machine, the springs 60 serving to urge the bar 54 toward the belt so as to firmly grip the stems at all times.

It will be particularly noted that while the leaves pass the sewing machine needle in a substantial horizontal position, they are shifted to a vertical position as they pass along the presser bar 54, so that when they reach the end of such bar, adjacent the block 61, they are hanging freely downward.

The apparatus for placing the tobacco strings upon the housing sticks will now be described. This part of the mechanism is supported by a cantilever bar 69, suitably secured to the frame 2, 3, at one end, and anchored to the bracket 62, as by means of a screw 70 (see Fig. 1). From this point, the bar is offset vertically, as shown at 69^a, and then extends in a substantially horizontal direction at a considerably higher level than the presser bar 54.

Depending from the supporting bar 69 are a pair of brackets 71 and 72, the former being secured by a bolt in any desired one of a series of holes 73 (see Fig. 2), whereby the distance between the brackets may be adjusted.

In the bracket 71 is journaled a sprocket wheel 74 and in the bracket 72 is journaled a sprocket wheel 75, and around these sprocket wheels passes an endless sprocket chain 76. This chain is driven by means of a pulley 78^a rigid with the sprocket wheel 75, by means of a belt 77 passing

around such pulley, and a driving pulley 78 on the upper end of the shaft 68.

Secured to the chain 76 at symmetrically spaced points thereof are a plurality of combined gripping and cutting devices 79, the details of which are most clearly illustrated in Figs. 3 to 5. Each of these devices, of which two are shown in the drawings, comprises a pair of jaws 80 and 81, pivoted at 82 to the body, the jaws being carried by arms 83, between which is interposed a spring 84 which normally tends to urge the jaws together, as shown in Fig. 4. The upper ends of the arms 83 diverge slightly and carry anti-friction rollers 85. These rollers are adapted to engage pairs of operating bars or ramps 86 and 87, supported by the brackets 71 and 72.

By reference to Figs. 5 and 5^b it will be seen that one of the jaws, such as 81, carries at one edge an upstanding knife or blade 81^a, the sharp edge of which is adapted to cooperate with the adjacent edge 80^a of the jaw 80 to produce a shearing action, like a pair of scissors. The inner faces of the jaws 80 and 81 are preferably roughened or knurled so as to provide gripping surfaces 81^b. From this, it will be seen that if a string or chain of stitches is interposed between the jaws when they are in the open position shown in Fig. 5, and the jaws then close to the position shown in Fig. 4, the cord or string will be severed or cut by reason of the shearing action of the parts 80^a and 81^a, while at the same time, the severed end of the cord or string will be firmly gripped by the surfaces 81^b of the jaws.

In the drawings, I have shown a channel shaped guide member 88 extending between the brackets 71 and 72 above the chain 76, for the purpose of maintaining the gripping devices in a vertical plane and guiding them as they travel along, although the stiffness of the chains 76 will, in most cases, be sufficient, and this guide may be omitted.

By reference to Figures 2 and 5^b, it will be seen that the pair of bars constituting the ramp 86 are parallel throughout a greater portion of the upper part of their length, and throughout that portion which encircles the pulley 74, but that the lower portion of these bars are disposed at a slight angle so as to provide diverging arms, as best shown in Fig. 5^b. When, therefore, one of the gripping devices 79 travelling toward the left, as viewed in Fig. 1 on the lower run of the chain 76, enters between the arms of the bars 86, the rollers 85 will engage these arms, and as the gripping device moves onward, the rollers 85 will be forced together and the jaws opened, as illustrated in Fig. 5.

As the gripping and cutting device 79 proceeds toward the right on the upper run of the chain 76, and encounters the ramp bars 87, the rollers are forced together by the flaring ends 87^a of such bars and the jaws are opened to the position shown in Fig. 5. The jaws are held in this open position as the device 79 travels around the pulley 75. The bars 87, however, terminate abruptly at a point just beneath the pulley 75, as shown at 87^b in Fig. 1, with the result that as the device 79 passes out from between these bars at this point, the spring 84 snaps the jaws 80 and 81 together, into the position shown in Fig. 4. Thus, the jaws come together as the gripping device leaves the bracket 72 and are opened as the device approaches the bracket 71.

Arranged beneath the travelling chain 76 and substantially in the same vertical plane, is an upstanding support shown as comprising a suitable

frame 89 over which are stretched smooth sheets 90, which may conveniently be of metal. As shown in Fig. 8, these sheets slightly converge, and at the upper end of the frame 89 is a horizontal member 89^a. The upper edges 91 of the sheets 90 project somewhat above the member 89^a so as to form a pocket or channel for the reception of a housing stick 92. This may be similar to that commonly employed for housing tobacco by other methods. The forward end of the supporting structure formed by the frame 89 and sheets 90 is preferably shaped to form a relatively sharp edge, like the bow of a boat, as indicated at 93, and mounted inside of this pointed end is a vertically disposed shaft 94, journalled to oscillate in the frame and having secured to its lower end an arm 95, connected by a rod 96 to the oscillating bell crank lever 52, above referred to (see Fig. 2^a), it being understood that the frame 89 is suitably anchored to the frame 2 of the rest of the apparatus, as by means of a bolt 2^a, (see Fig. 1).

To the upper end of the shaft 94, immediately above the structure 89, 90, is secured a finger 97, extending toward the presser bar 54. This finger is disposed in the path of the string of tobacco leaves, passing from the bar 54, and has its end preferably rounded or provided with a knob, as shown, so as to avoid injury to the leaves. It will, of course, be understood from what has been said that as the machine operates, the finger 97 oscillates from side to side in a horizontal plane.

The operation of the apparatus as a whole will be briefly described. The tobacco leaves, having been previously pulled, or stripped from the stalk, are delivered upon the sorting table 1. The operator then places the leaves upon the conveyor belt 8 with the ends of the stems abutting against the gauge board 47, the leaves being placed on the conveyor in more or less closely associated relation but usually in such a manner that considerable space exists between the stems themselves. The leaves travel toward the left, as viewed in Fig. 2^a and are finally engaged by the forced feed belt 39 and carried under the presser bar 54, which preferably has an upturned end. The leaves then pass successively under the needle of the sewing machine, the needle piercing the stems and forming a continuous series of stitches, some of such stitches piercing through the stems and others merely forming a chain between successive stems and connecting the same. As the stems are discharged from the feed belt 39, they are engaged by the second feed belt 65 and the string of connected leaves is fed forward by the belt 65, being carried between such belt and the presser bar 54, the leaves, when they reach the left hand end of such bar, hanging in substantially vertical position, as above described.

In beginning the operation of the machine, it is necessary to manually engage the forward end of the string in one of the gripping devices 79, such device being located adjacent the bracket 72 as shown in Fig. 1. Then, as the machine continues to run, this gripping device will travel toward the left and draw the string of leaves with it, in a direction parallel with the supporting structure 89, 90 and above and lengthwise of the housing stick 92 held by such structure. As the string is drawn along toward the left, as viewed in Fig. 1, the successive leaves encounter the oscillating finger 97 and this finger serves to divert or direct successive leaves alternately to opposite sides of the support. It may be explained

that by the expression "successive leaves alternately", I do not mean to be limited to an operation in which each individual successive leaf is necessarily deflected to opposite sides of the support. It will be appreciated, of course, that the finger 97 will not always necessarily throw successive leaves alternately to opposite sides of the support, but it will produce substantially this effect, that is to say, it will direct or deflect some of the leaves to one side of the support and some to the other. This results in the string being drawn endwise along the support with the leaves astride the same, so that when the string has been moved the full length of the support, and the housing stick 92 is then lifted, it will engage and carry with it the string of leaves, such string being disposed longitudinally of the stick and astride the same, with some leaves on one side and some on the other, substantially as illustrated in Fig. 9.

I have described the clutch device 11 and the arcuate slot 18 in the wheel 17 for operating the same. It will therefore be understood that as the apparatus is continuously driven, and the sewing machine runs continuously and continuously forms a series of chain stitches, the travel of the conveyor belt 8 is periodically and momentarily interrupted, and thus the feeding of leaves is similarly periodically interrupted. This results, therefore, in the production of a continuous string of leaves in which the leaves are arranged in groups, such groups being connected solely by a chain of stitches. The length of this connecting chain of stitches or, in other words, the spacing of the groups of leaves from each other, is of course determined by the length of the slot 18, and this may be made as long as desired. The mechanism is so timed, however, and the parts are so proportioned that the lengths of the groups of leaves is substantially equal to the length of a housing stick, or rather slightly less than such length. Also, the length of the groups of leaves is slightly less than the distance between the two gripping devices 79.

Assuming the apparatus to be in operation, as described, it will now be understood that one gripping device is always in engagement with the front end of the string and serves to draw it along toward the left, as viewed in Fig. 1, depositing the string astride the housing stick 92. As this gripping device 79 on the lower run of the chain enters between the arms of the ramp bars 86, it is opened as shown in Fig. 5, and releases the end of the string. Substantially at the same moment, the other gripping device travels down around the ramp bars 87, with its jaws in open position, as shown in Fig. 5, and these jaws engage over the string in the space between two successive groups of leaves. As this gripping device snaps out from between the ends 87^b of the bars 87, it serves to simultaneously sever the string and grip the severed end.

The above operation therefore takes place continuously, the string being drawn forward by the two gripping devices operating alternately, and the string being severed into sections of unit length, as each gripping device engages the string adjacent the ramp bars 87. The unit lengths of string are thus successively placed astride the supporting structure 89, 90, and the attendant merely inserts successive housing sticks 92 in position and then lifts them out of the support with the string sections astride of the sticks, as shown in Fig. 9.

Finally, it will be understood that the cutting

and gripping devices successively engage the string at about midway of the space between the groups of leaves, so that when the string is severed at this point, there remains a projecting end 5 or cue of chain stitches on each side of each group of leaves. In Fig. 9, the chain of stitches is indicated at *x*, the projecting end or cue at *y*, while the leaf stems are shown at *z*.

As is well known, it is a characteristic of chain 10 stitches, either single or double, that they can be easily unravelled merely by pulling on the end of the thread. When, therefore, it is desired to unstring the tobacco leaves for packing or manufacture, the thread can be readily stripped from 15 the leaves by pulling out the chain stitches, thus leaving the tobacco entirely free from thread.

While I have shown and described certain details of construction, it will, of course, be understood that these are illustrative only and that the 20 invention is by no means limited to the exact construction shown. Variations and modifications falling within the scope of the invention will, of course, readily suggest themselves to those skilled in the art.

25 What I claim is:

1. Apparatus for stringing tobacco comprising a sewing machine, means for feeding tobacco leaves sidewise and for causing their stems to pass successively under the needle of said machine, whereby said leaves are united to form a string, and traveling means, in addition to said feeding means, and unattached to said leaves, for supporting and carrying said completed string away from said needle, said traveling means being constructed to progressively turn said string of leaves from a horizontal position to a position in which the leaves hang vertically downward.

2. Apparatus for stringing tobacco comprising means for continuously forming a string of leaves 40 with the leaves arranged on the string in spaced groups, means for feeding the string along, and means for severing the string at points between said groups to form units for housing.

3. Apparatus for stringing tobacco comprising 45 means for continuously forming a string of leaves with the leaves arranged on the string in spaced groups, means for feeding the string along, means for severing the string at points between said groups to form units for housing, and means for 50 positioning each group longitudinally astride a housing stick, with some of the leaves on one side and some on the other.

4. Apparatus for stringing tobacco comprising

means for continuously forming a string of leaves with the leaves arranged on the string in spaced groups, means for supporting in horizontal position a housing stick of approximately the same length as said groups, means for feeding said string along said stick with some leaves on one side and some on the other, and means for severing the string at the rear of each group after the group has been positioned over the said stick.

5. Apparatus for handling tobacco comprising 10 means for forming the leaves into a string, means for supporting a housing stick, means for drawing said string endwise along said stick, and means for directing leaves alternately to opposite sides of the stick as the string travels on to the same.

6. Apparatus for handling tobacco comprising means for forming the leaves into a string, means for supporting a housing stick, in horizontal position, an endless carrier having one run disposed above and substantially parallel with said stick, 20 means on said carrier for gripping said string to draw it forward over said stick, and automatic means for releasing said gripping means when the string has traveled the desired distance along said stick.

7. Apparatus for handling tobacco comprising means for continuously forming the leaves into a string, and automatic means for drawing said string continuously forward and for cutting it into successive unit lengths.

8. Apparatus for handling tobacco comprising means for continuously forming the leaves into a string, an endless traveling carrier, a plurality of combined gripping and cutting devices on said carrier spaced apart a distance equal to the length 35 of the sections into which it is desired to cut the string, and means for successively causing one of said devices to grip the forward end of the string and draw it along with the carrier, and another of said devices to engage the string and 40 simultaneously cut off the section of string between said devices and grip the forward end of the following portion of the string.

9. In tobacco handling apparatus, the combination with an upstanding, elongated, narrow 45 support, of means for forming a string of leaves and drawing said string endwise over said support, and an oscillatory finger mounted at the end of said support and serving to direct successive leaves of the string to opposite sides of the support as the string travels along.

JOHN ROBERT BASS.
